ATTORNEY

UNITED STATES PATENT OFFICE.

JÓSEF CHMIELEWSKI, OF NEW BRITAIN, CONNECTICUT.

DESIGN FOR A COMBINATION CANE AND UMBRELLA LIGHT.

56,737.

Specification for Design.

Patented Dec. 14, 1920.

Application filed June 15, 1920. Serial No. 389,243. Term of patent 3½ years.

To all whom it may concern:

Be it known that I, JÓSEF CHMIELEWSKI, a citizen of Poland, and a resident of New Britain, in the county of Hartford and State of Connecticut, have invented a new, original, and ornamental Design for a Combination Cane and Umbrella Light, of which the following is a specification, reference being had to the accompanying drawings, forming part thereof.

The figure is a front view of a combination cane and umbrella light, showing my new design.

I claim—

The ornamental design for a combination cane and umbrella light, as shown.

JÓSEF CHMIELEWSKI.
